UNITED STATES PATENT OFFICE.

CHARLES ARTHUR SPEAKMAN, OF NEW YORK, N. Y., ASSIGNOR TO THE AMERICAN LITHOGRAPHIC COMPANY, OF SAME PLACE.

DESIGN FOR A LABEL.

SPECIFICATION forming part of Design No. 30,711, dated May 9, 1899.

Application filed April 8, 1899. Serial No. 712,832. Term of patent 7 years.

To all whom it may concern:

Be it known that I, CHARLES ARTHUR SPEAKMAN, a citizen of the United States, residing at New York city, in the county of New York and State of New York, have invented and produced a new and original Design for a Label, of which the following is a specification, reference being had to the accompanying drawing, forming a part thereof.

10 My design is intended for use as a label.

In the accompanying drawing the design is shown on a rectangular panel.

15 The design comprises one large irregular panel (designated by letters A A) outlined by scrollwork and cut nearly through the center horizontally by a curving line of five medals B, above the center of which is shown a bunch of leaves and blossoms C. An eagle with outspread wings standing upon a shield similar

to that used in the coat of arms of the United States surmounts the design, and a circle of rays is shown rising behind it. Groups of palm-leaves are represented as emerging from behind the panel at either side of the design. At the two lower corners are respectively to the left the dome of the Capitol at Washington and to the right Morro Castle at Havana.

I claim—

20 The design for a label as herein shown and described.

25 In testimony whereof I, C. ARTHUR SPEAKMAN, affix my signature in the presence of two witnesses.

30 C. ARTHUR SPEAKMAN.
